MOP WRINGER

George A. Reitzel, St. Louis, Mo.

Application December 31, 1931, Serial No. 584,031

6 Claims. (Cl. 15—261)

This invention relates to new and useful improvements in mop wringers and mops used in conjunction therewith.

The objects of the invention are to provide a mop wringer which is of simple but rugged construction and which engages the mop while the latter is held stationary in said wringer and extracts the water from said mop in an efficient manner.

10 Other objects of the invention are to provide a mop wringer having its front wall formed with a seat to receive a mop and hold it in a vertical position with the mop strings presented inwardly, there being movably mounted in said wringer a 15 vertically disposed presser plate movable under pressure against said mop to extract water from said mop strings.

Further objects of the invention are to provide a mop having a back and a handle connected thereto, the mop strings being carried by a plate which in substantially coextensive with said back and is detachably secured thereto so that it can be replaced when worn.

Additional objects of the invention are to provide a mop wringer which is compact in construction, can be easily attached to a pail and supported independently thereof, and which is adapted to receive a mop of special construction and engage under pressure the entire mop string 30 surface thereof to extract the water therefrom while said mop is held immovable in said wringer.

With these and other objects in view, my invention consists in certain novel features of construction and arrangement of parts, hereinafter more 35 fully described and claimed and illustrated in the accompanying drawings, in which—

Figure 1 is a side elevational view of my mop wringer showing the pail in dotted lines.

Figure 2 is a front elevational view of the mop 40 wringer.

Figure 3 is an enlarged vertical cross section taken on line 3—3 of Figure 2.

Figure 4 is an enlarged horizontal cross section taken on line 4—4 of Figure 1 and showing the 45 mop in position therein and the mop wringer in actuated position to engage the mop strings and extract water therefrom.

Figure 5 is a top plan view of my improved mop. Figure 6 is a vertical cross section taken on line 50 6—6 of Figure 5.

Figure 7 is an enlarged horizontal cross section through the forward end of the mop.

Briefly stated, the mop which is of special construction is adapted to fit in a seat formed in the 55 front wall of the wringer with the mop strings

presented inwardly and engaged by a movable plate of said wringer to extract water from said strings.

Referring by numerals to the accompanying drawings, 10 indicates a body portion of the mop 60 wringer and 11 a pail to which it is attached. The body portion consists of an elongated hollow member open at both upper and lower ends 12 and 14, respectively.

It is substantially rectangular in cross section 65 having a rear wall 15, side walls 16, and a front wall 17.

The lower portion 18 of front wall 17 is slotted vertically and centrally, as indicated at 19, to permit the handle 20 of a mop 21 to pass upwardly therethrough. The upper portion of said front wall 17 is cut away to form vertically disposed oppositely and inwardly presented flanges 22. These flanges are arranged in a vertical plane spaced outwardly from lower portion 18, as 75 shown in Figure 1. They are of sufficient widths to receive and engage the side edges of the back 21a of said mop when the latter is placed in position in the wringer.

The forward end of the back 21a is formed 80 pointed as indicated at 21b and terminates in an outwardly curved rubber insert or bumper 23. The mop strings 24 are attached to a plate 25 which bears against the underside of back 21a and fits within the downwardly presented marginal flanges 21c of said back. A screw 26 passes through an aperture formed in one of the flanges 21c and engages the plate 25, thereby securing the latter to the back 21a.

A socket member 20a is provided at its lower 90 ends with flanges 20b which are secured to the back 21a by rivets 27. Handle 20 engages said socket member and extends outwardly therefrom, preferably at an angle from vertical. A screw 28 takes the place of one of the rivets 27 and 95 extends through back 21a and engages said plate 25, as shown in Figure 6, thereby providing further attaching means for securing the plate and mop strings in position.

The lower portion of the socket member 20a is 100 of less width than the width of slot 19 so that the mop can be moved upwardly through said wringer. The mop is placed in position therein with the pointed end 21b presented downwardly. The lower portion 18 of the front wall 17 has its upper 105 corners offset laterally so that they are located in the same vertical plane with the flanges 22 and form a seat for said pointed end 21b of said mop, as shown in dotted lines in Figure 3.

When thus positioned the back 21a is disposed 110

vertically with the mop strings 24 presented inwardly. A bell crank 29 is disposed in body portion 10 and has its ends journaled in the side walls 16 near the rear wall 15 substantially in 5 horizontal plane with said offset corner portions 18a.

Preferably a reinforcing member 30, channel-shaped in cross section, encircles the body portion 10 and has its ends terminating adjacent to the 10 offset corner portions 18a. This reinforcing member is secured to the respective walls of said body portion by rivets 31 and forms a bearing for the ends of bell crank 29.

The central or offset portion 29a of said bell 15 crank is disposed within said body portion and has loosely mounted thereon a roller 32 which bears against a track 34 vertically disposed in said body portion.

This track is fixed to a presser plate 35 which 20 latter extends between the side walls 16 while the track plate is comparatively narrow. The upper end 35a of said presser plate extends slightly above the open upper end 12 of said body portion 10 and the lower end 35b extends a suitable 25 distance below the lower end 14 of said body portion and is disposed within the pail 11.

A retainer 36 is secured at its upper end to the 30 rear face of track 34 and extends downwardly in spaced relation therewith and overlies said roller 32. Thus said roller supports the track member 34 and presser plate 35 and is held at all 35 times in operative engagement therewith.

One end of the bell crank 29 is provided with a handle 37 whereby presser plate 35 can be actuated manually toward the mop placed in said body portion. A coiled spring 38 cooperates with the other end of said bell crank and serves to move the latter in opposite direction and move said presser plate away from said mop. Preferably said presser plate is provided with a plurality of apertures 40 to facilitate the extraction of water from the mop strings when said presser plate is forced thereagainst.

The mop wringer can be supported in any suitable manner on the pail. Preferably the lower ends of said walls 16 are provided with vertically disposed slots 41 which are adapted to receive the upper end of a plate, thereby supporting said mop wringer in position thereon. In order to 45 eliminate sharp edges from bearing against the peripheral wall of the pail, walls 16 are provided with suitable castings 42 having slots 44 which coincide with slots 41 and having laterally and outwardly projecting flanges 45 which increase 50 the surface contact between the wall of the pail and the mop wringer.

The pail 11 is preferably provided with a foot or extension 11a extending radially and outwardly from the lower end of the pail and arranged 55 below said mop wringer so that the weight of the latter cannot up-turn said pail.

The upper end 12 of said body portion is preferably reinforced by a member 46 which is secured to the upper edge of the walls of said body portion and provides stiffening therefor. A U-shaped handle 47 is secured to said member 46 and to said walls 16 and provides convenient means for carrying said mop wringer.

Normally the mop wringer mechanism occupies 70 positions shown in Figures 1 and 3 in which position the presser plate is retracted. When a mop is inserted into the mop wringer, as shown in dotted lines in Figure 3 and in cross section in Figure 5, handle 37 is operated to move the presser plate 35 forwardly against the mop strings 24.

The pressure thus applied against said strings causes the water to be squeezed therefrom. As the lower end 14 of said body portion and the lower end 35b of said presser plate 35 are located within the pail 11 the water extracted from the 75 mop strings drains into said pail. When the handle 37 is released, coil spring 38 causes the bell crank 29 to move into normal position (shown in Figs. 1 and 3) thereby moving the presser plate 35 away from the mop. Members 30 and 46 reinforce said body portion 10 and prevent any distortion thereof from undue pressure applied by the presser plate. The lower ends of said walls 16 are preferably flared outwardly so as to facilitate the insertion of the mop within the body portion 10.

My improved mop wringer is of simple but rugged construction, can be easily moved and applied to any pail, and is highly efficient in performing its intended functions. The mop used in conjunction with my mop wringer has the mop string holder formed removable so that the latter can be readily depressed. The rubber tip with which my mop is provided prevents injury to the furniture or to the wall.

I claim:

1. A mop wringer comprising in combination, a vertically disposed open-ended body portion rectangular in cross section and having its front wall slotted vertically whereby a mop having a flat 105 back can be inserted therein with said back arranged against said front wall and the mop strings presented inwardly, a bell crank operatively mounted in said body portion adjacent to the rear wall thereof, and a vertically disposed 110 presser plate mounted in said body portion for transverse movement and operable by said bell crank against said mop strings to squeeze water therefrom.

2. A mop wringer comprising in combination, a 115 vertically disposed open-ended body portion rectangular in cross section and adapted to be supported over a pail, said body portion having its front wall slotted vertically to receive a mop having a flat back with the latter bearing against 120 said front wall and the mop strings presented inwardly, a bell crank operatively mounted in the side walls of said body portion adjacent to the rear wall thereof, a presser plate vertically disposed in said body portion and operatively supported by said bell crank, said presser plate being movable transversely in said body portion in parallel relation with the back of said mop, a handle connected to one end of said bell crank for manually actuating the latter and moving 125 said presser plate against said mop strings, whereby the latter are placed under pressure and the water extracted therefrom, and a spring cooperating with said bell crank for returning the latter and said presser plate to normal positions.

3. A mop wringer comprising in combination, a vertically disposed open-ended body portion rectangular in cross section and having the lower ends of its side walls formed with vertically disposed downwardly opening slots for engaging the upper end of a pail, said body portion having its front wall slotted vertically to receive therein a mop having a flat back disposed vertically against said slotted wall with its mop strings presented inwardly, a bell crank operatively mounted in the side walls of said body portion and extending through the latter adjacent to the rear wall thereof, a presser plate disposed vertically in said body portion and operatively supported by said bell crank, said presser plate being movable trans-

- versely in said body portion parallel with said mop, a reinforcing member secured to the walls of and partially encircling said body portion intermediate the ends thereof and forming bearings 5 for the ends of said bell crank, a handle secured to one end of said bell crank for manually operating the latter and forcing said presser plate under pressure against said mop strings, and a coiled spring engaging said body portion and the 10 opposite end of said bell crank for maintaining the latter and said presser plate in normal or remote position with respect to said mop.
4. In a mop wringer, the combination of a box-shaped open ended body portion having its front 15 wall vertically slotted, said body portion being adapted to receive a mop having a flat back provided with mop strings on one side and a handle on the other, said flat back bearing against said front wall with said handle extending outwardly 20 through said slot and with said mop strings presented inwardly, a horizontally disposed bell crank extending through said body portion and having its ends operatively mounted in the side walls of said body portion adjacent to the rear 25 wall thereof, a presser plate disposed in said body portion and transversely movable therein in parallel relation with said mop, means for operatively supporting said presser plate on said bell crank, a handle secured to one end of said bell crank for 30 operating it and said presser plate toward said mop strings and squeeze water therefrom, and a coiled spring for returning said bell crank and presser plate to normal or disengaged position.
5. A mop wringer comprising in combination 35
- an open-ended body portion rectangular in cross-section and having its front wall provided with a vertically disposed slot whereby a mop having a flat back and a handle extending therefrom can be placed in said body portion with its back against said front wall and the mop strings presented inwardly and with the handle extending outwardly through said slot, a plate movably mounted in said body portion for movement to and from said front wall and substantially in parallelism therewith, means for moving said plate forwardly to apply pressure against said mop strings, and means for retracting said plate.
6. A mop wringer comprising in combination 40 an open-ended body portion rectangular in cross-section and having a front wall provided with a vertically disposed slot whereby a mop having a flat back and a handle extending therefrom can be placed therein with its back against said front wall and the mop strings disposed inwardly and with said handle extending outwardly through said slot, said body portion being preferably made of sheet metal, a reinforcing band secured externally to said body portion and partially encircling the same, a plate movably mounted within 45 said body portion for movement to and from said front wall and substantially in parallelism therewith, a manually operable crank shaft arranged within said body portion and having its ends journaled in said reinforcing band, said shaft having a pivotal connection with said plate for actuating the latter, and a spring for retracting said crank shaft and said plate.
